The Hettrick Manufacturing Company, Toledo, Ohio, a corporation of Ohio

Application March 11, 1936, Serial No. 61,579

Term of patent 7 years

To all whom it may concern:

Be it known that I, Milton B. Smith, a citizen of the United States and resident of Perrysburg, county of Wood, State of Ohio, have invented a new, original, and ornamental Design for a Can-opy Glider, of which the following is a specification, reference being had to the accompanying drawing forming a part thereof.

In the drawing—

The figure is a perspective view of the canopy glider showing my new design.

I claim:

The ornamental design for a canopy glider, as shown.

In testimony whereof I have hereunto signed
my name to this specification.

MILTON B. SMITH.
